UNITED STATES PATENT OFFICE

HAROLD H. RUGG, OF WILKINSBURG, PENNSYLVANIA, ASSIGNOR TO WESTINGHOUSE ELECTRIC & MANUFACTURING COMPANY, A CORPORATION OF PENNSYLVANIA

CIRCUIT BREAKER APPARATUS

Application filed November 23, 1928. Serial No. 321,407.

My invention relates to circuit breaker apparatus and particularly to apparatus of the truck-panel type wherein the circuit breaker is enclosed within a cell structure and may be disconnected from the feed conductors and withdrawn from the cell for the purpose of inspection and repair, or for substitution of another circuit breaker.

An object of my invention is to provide a truck panel circuit breaker wherein the circuit breaker unit is moved into the cell in a horizontal plane and moved vertically upward into engagement with stationary contacts within the cells that are connected to the feed bus bars.

A further object of my invention is to provide a means for guiding the movement of the circuit breaker within the cell structure and a means for supporting the circuit breaker in an elevated operative position in such manner that the supporting means cannot be released until the circuit breaker is supported upon a truck used for supporting the circuit breaker while it is being moved into the cell and elevated to the operative position.

A further object of my invention is to provide a circuit breaker having the above-noted characteristics wherein means are provided for preventing the circuit breaker from being moved to either the operative or the inoperative position while the circuit breaker contacts are in the closed position.

These and other objects that will be made apparent throughout the further description of my invention, are attained by means of the circuit breaker apparatus hereinafter described and illustrated in the accompanying drawings, wherein:

40 Figure 1 is an elevational view of a circuit breaker apparatus embodying features of my invention, the cell structure being shown in vertical section;

45 Fig. 2 is an elevational view of the circuit breaker apparatus shown in Fig. 1 showing the circuit breaker in an inoperative lower position wherein it is being withdrawn horizontally from the cell, and;

50 Fig. 3 is an end elevational view of the circuit breaker apparatus shown in Fig. 1.

Referring to the drawings, the apparatus comprises a sheet metal cell structure 4 having side walls 5, a top wall 6 and a rear wall 7. The side walls 5 are provided with false walls 8, the purpose of which will more fully hereinafter appear.

The top wall 6 supports insulator bushings 9 which support the fixed contacts 11 that are connected to the feed busses 12. The contacts 11 are adapted to be engaged by disconnect contacts 13 that are carried by insulating bushings 14 mounted upon the cover 15 of a metal circuit breaker housing 16.

It will be understood that the circuit breaker unit may be of any preferred construction that includes the manual operating devices 17 and an electromagnetic closing and trip device 18 for closing the circuit breaker electrically, or causing it to be tripped to the open position in response to severe overload or short circuit conditions.

An elevator truck 19 is provided for moving the circuit breaker unit into the cell and for elevating it to the operative position, in which it is supported independently of the truck by means that will be hereinafter described. The truck comprises a base frame 21 provided with rollers 22 and a pair of vertical standards or guide posts 23. A cross head 24 is slidably mounted upon the guide posts and receives a threaded screw 25 which is supported in a connecting bar 26 which serves to join the upper ends of the guide posts. The screw is provided with fixed collars 27 for preventing longitudinal movement of the screw with respect to the cross bar 26. It will be seen from the foregoing that when a hand wheel 28, secured to the upper end of the screw 25, is rotated, the cross head 24 will be moved upwardly or downwardly, depending upon the direction of rotation of the hand wheel.

A carrier frame 29 is rigidly connected to the cross head 24 and comprises two spaced frame structures each having a recess 31 for receiving a supporting pin 32 carried by the circuit breaker unit 16. The frames 29 are also provided with extensions 33, the purpose of which will hereinafter appear. The lower

end of the circuit breaker housing 16 is provided with a lug 34 which supports a bar 35 that engages the lower end of the carrier frame 29 and thus serves to maintain the circuit breaker unit in vertical position when supported upon the carrier frame 29.

- The base frame 21 of the truck is so designed that portions thereof straddle the circuit breaker housing, thereby permitting the truck to be moved into operative position with respect thereto, in order that the notches 31 may be disposed beneath the pins 32 on the circuit breaker when it is desired to support the circuit breaker upon the truck.
- 15 When the cross head 24 is elevated by turning the hand wheel 28, the carrier frame 29 will cause the circuit breaker to be raised from the floor and supported entirely upon the truck. The circuit breaker may then be moved into the cell 4.

The cover of the circuit breaker is provided with a frame structure 36 which carries a pair of rollers 37 which move in the horizontal guide-way 38 of a guide member 39 when the circuit breaker is being moved horizontally into the cell. The guide member 39 is provided with a pair of vertical guide-ways 41 for receiving the rollers 37 and guiding the vertical movement of the circuit breaker 30 after it has completed its movement into the cell. At this time, the hand wheel 28 is rotated to elevate the carrier 29 and thereby move the circuit breaker unit vertically until the disconnect contacts 13 fully engage the stationary fixed contacts 11 in the cell, as indicated in Fig. 1.

In order to support the circuit breaker in the operative position and to permit the removal of the truck, I have provided each side wall of the cell with a pair of rotary latches 42 that are rotatably mounted upon the false wall 8 and which are provided with slots 43 that register with the vertical guide-ways 41 and receive the rollers 37 on the circuit breaker unit. The rotary latches 42 are provided with crank arms 44 that are pivotally connected to one another by a connecting rod 45 in such manner that the rotary latch nearest the open front of the circuit breaker cell is rotated in a counterclockwise direction and the other latch is rotated in a clockwise direction. The foremost disposed rotary latch 42 is provided with an operating handle 46 of U-shape which serves 55 to simultaneously rotate the rotary latches on both side walls of the cell.

After the rollers 37 have been moved into the slots 43 in the rotary latches 42, the operating handle 46 is moved downwardly to 30 the position shown in Fig. 1 causing the notches 43 to be moved to a horizontal position in such manner that the rollers are confined in the notches and any vertical or lateral displacement of the circuit breaker unit prevented. The circuit breaker is, at

this time, entirely supported by the rotary latches and the carrier 29 of the truck may be lowered away from the circuit breaker and withdrawn from the cell.

In order to prevent releasing movement 70 of the rotary latches 42 except when the truck is in position to support the circuit breaker unit, I have provided a pair of interlocking bars 47 that are mounted in the space between the false walls 8 and the side walls 5 and which are provided with pins 48 and 49 that are respectively engaged by a lug 51 on the connecting rods 45 and the extensions 33 on the carrier frame 29.

It will be seen by reference to Fig. 2 that 80 no movement of the rotary latches 42 can be accomplished until the pin 48 has been raised out of the path of the lug 51. When the carrier frame 29 has been moved to its extreme upper position wherein the circuit breaker is moved to the operative position, the extensions 33 engage the pins 49 on the bars 47 and move the pins 48 clear of the lugs 51. The latches 42 may then be rotated to cause the circuit breaker to be located in 85 its operative position and supported entirely upon the latches. When the truck has been removed, the bar 47 returns to its lowermost position and causes the pins 48 to be disposed again in the path of the lug 51 and prevent 90 releasing movement of the rotary latches. By reason of this interlock, the circuit breaker cannot be released until the truck has again been placed beneath the circuit breaker to receive it, at which time, the interlocking bar 47 is elevated to the releasing 100 position.

It is quite important that the circuit breaker shall be in open position when the circuit breaker unit is moved to either the operative or the inoperative position, and, for this purpose, I have provided means for causing the circuit breaker to be tripped to the open position upon initial disengaging movement of the circuit breaker unit from the contacts 11 or upon initial elevating movement of the circuit breaker unit toward its operative position.

This apparatus comprises a lever 52 pivotally mounted upon the electromagnet 18 and which serves to trip the circuit breaker controlling mechanism to release the circuit breaker contacts to open position when the lever is rotated in a clockwise direction about the pivot shaft 53. The lever 52 is rotated clockwise upon initial disengaging movement of the circuit breaker unit by means of a cam shoe 55 carried on the side walls 4 of the cell structure, the ends of the shoe 55 being bent inwardly to present an inclined surface to a pin 54 carried on the free end of the lever 52.

Referring to Fig. 1, it will be seen that the pin 54 is in engagement with the upper end of the cam shoe 55 and will cause the 120

circuit breaker to be tripped open upon initial downward movement of the circuit breaker unit. When the circuit breaker unit is in its lowermost position and fully moved into the cell, the pin 54 of the lever 52 will occupy a position in contact with the inclined lowermost end of the cam shoe 55. Initial upward movement of the circuit breaker unit will cause clockwise rotation of the lever 52 and trip the circuit breaker to open position. It is, therefore, impossible to connect the circuit breaker unit with the contacts 11 or to disconnect the unit therefrom without first causing the circuit breaker to be opened when contact is actually made or before contact is actually broken between the contacts 11 and the disconnect contacts 13.

It will be seen from the foregoing that I have provided a simple and positive means for supporting a circuit breaker unit within a cell structure in such manner that false operations cannot be accomplished and that the construction is rugged and effective in operation.

25 While I have illustrated but one embodiment of my invention, it will be apparent to those skilled in the art that various changes, modifications, substitutions, additions and omissions may be made in the apparatus illustrated without departing from the spirit and scope of my invention, as set forth in the appended claims.

I claim as my invention:

1. Circuit breaker apparatus comprising a support having a rotary latch provided with a slot, a circuit breaker having a projection for entering the slot and means for turning the latch to prevent the projection from disengaging from the latch.

40 2. Circuit breaker apparatus comprising a support having a pair of rotary latches provided with a slot, a circuit breaker having a pair of projections for entering the slot and means for simultaneously turning the latches to prevent the projections from disengaging from the latches.

45 3. Circuit breaker apparatus comprising a support having a rotary latch provided with a slot, a circuit breaker having a projection for entering the slot, means for turning the latch to prevent the projection from disengaging from the latch and movable means for preventing releasing movement of the latch.

55 4. Circuit breaker apparatus comprising a support having a rotary latch provided with a slot, a circuit breaker having a projection for entering the slot, means for turning the latch to prevent the projection from disengaging from the latch, means for raising and lowering the circuit breaker and means actuated by the last said means for preventing releasing movement of the latch.

60 5. Circuit breaker apparatus comprising a cell having side walls, a circuit breaker

having disconnect contacts and movable into and out of the cell in a horizontal plane and movable vertically within the cell, contacts within the cell adapted to be engaged by the disconnect contacts when the circuit breaker is moved vertically to operative position, a pair of rollers on each side of the circuit breaker, horizontal guides on the side walls and for the rollers upon which the circuit breaker is moved into the cell, a pair of vertical guides on each side wall for receiving the rollers and guiding the vertical movement of the circuit breaker, rotary latches aligned with the vertical guides and mounted on the side walls and having slots therein for receiving the rollers and means for turning the latches to prevent the rollers from becoming disengaged therefrom and thereby causing the latches to support the circuit breaker.

6. Circuit breaker apparatus comprising a cell having side walls, a circuit breaker having disconnect contacts and movable into and out of the cell in a horizontal plane and movable vertically within the cell, contacts within the cell adapted to be engaged by the disconnect contacts when the circuit breaker is moved vertically to operative position, a pair of rollers on each side of the circuit breaker, horizontal guides on the side walls and for the rollers upon which the circuit breaker is moved into the cell, a pair of vertical guides on each side wall for receiving the rollers and guiding the vertical movement of the circuit breaker, rotary latches aligned with the vertical guides and mounted on the side walls and having slots therein for receiving the rollers, means for turning the latches to cause them to support the circuit breaker, and means for preventing releasing movement of the latches except when the circuit breaker is supported independently of the latches.

In testimony whereof, I have hereunto subscribed my name this 19th day of November, 1928.

HAROLD H. RUGG.
